[57] CLAIM

The ornamental design for a child's bootie, as shown and described.

DESCRIPTION

FIG. 1 is a perspective of a child's bootie showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof, the right side elevational view being generally a mirror image thereof;

FIG. 7 is a perspective view of a child's bootie showing a second embodiment of our new design;

FIG. 8 is a perspective of a child's bootie showing a third embodiment of our new design;

FIG. 9 is a perspective view child's bootie showing a fourth embodiment of our new design; and,

FIG. 10 is a perspective view of a child's bootie showing a fifth embodiment of our new design.

All other views of the embodiments shown in FIGS. 7 through 10 are generally the same as FIGS. 2 through 6, except for minor changes in certain features which are apparent from FIGS. 7 through 10.

FIG. 1

FIG. 6

FIG. 2

FIG. 3

FIG. 4

FIG. 5

FIG. 9

FIG. 10

UNITED STATES PATENT AND TRADEMARK OFFICE
CERTIFICATE OF CORRECTION

PATENT NO. : Des. 327,361
